ATTORNEY

UNITED STATES PATENT OFFICE.

SIDNEY A. KELLER, OF NEW YORK, N. Y., ASSIGNOR TO MARCUS T.
GOLDSMITH, OF NEW YORK, N. Y.

DESIGN FOR A BAG-FRAME.

SPECIFICATION forming part of Design No. 35,464, dated December 24, 1901.

Application filed September 21, 1901. Serial No. 76,077. Term of patent 8½ years.

To all whom it may concern:

Be it known that I, SIDNEY A. KELLER, a citizen of the United States, and a resident of New York, in the county of New York and State of New York, have invented and produced a certain new and useful Design for Bag-Frames, of which the following is a specification.

In the accompanying drawing, to which reference is made and which forms a part of this specification, the figure illustrates a frame for bags in accordance with my design.

The leading features of my design consist of a curve at the lower edge, a short central curve at the upper edge, and two scallops at each side of the said central curve, the space between the edges being embossed in relief ornamental work.

In the drawing, A designates the lower

curved edge, B the short central curve at the upper edge, and C C and D D the two scallops at each side of the said central curve. The surface between the curve A, the short central curve B, and the scallops C C is ornamented with three faces, one beneath each of the curves B and C C, and with volutes and foliations surrounding each face. The surfaces between the curved edge A and the scallops D D are ornamented each with flower volutes and foliations, as shown.

What I claim is—

The design for a bag-frame, substantially as herein shown and described.

SIDNEY A. KELLER.
